United States Patent

Des. 241,324

Patented Sept. 7, 1976

241,324

NESTING CART

Leonard E. Wright, Paradise Valley, Ariz., assignor to Tradewinds Industries, Inc., Liberal, Kans.

Filed Jan. 31, 1975, Ser. No. 545,813

Term of patent 14 years

Int. Cl. D12—02

U.S. Cl. D12—29

FIG. 1

FIG. 2

FIG. 1 is an isometric view of a nesting cart showing my new design:

FIG. 2 is a bottom plan view thereof;

FIG. 3 is a side elevational view thereof; and

FIG. 4 is an end elevational view thereof opposite to that shown in FIG. 1.

I claim:

The ornamental design for a nesting cart, substantially as shown.
